His Attorney.

UNITED STATES PATENT OFFICE.

FRANK J. HUSBANDS, OF LOS ANGELES, CALIFORNIA.

TRAFFIC-SIGNAL.

1,335,240.

Specification of Letters Patent. Patented Mar. 30, 1920.

Application filed March 11, 1918. Serial No. 221,811.

To all whom it may concern:

Be it known that I, FRANK J. HUSBANDS, a citizen of the United States, residing at Los Angeles, in the county of Los Angeles 5 and State of California, have invented new and useful Improvements in Traffic-Signals, of which the following is a specification.

The present invention pertains to an improved signal apparatus that has been designed for the purpose of guiding and directing traffic at street intersections, the invention serving to aid the traffic officer, or acting as a substitute for him, and is designed as an improvement on the device 15 shown and described in Letters Patent of the United States, No. 1,236,441, granted to me on the fourteenth day of August, 1917.

In accordance with the embodiment of this invention, means are devised for the display of signals at each corner of intersecting streets with each signaling means facing in the direction of the approaching traffic, and operative so that traffic permission will be open alternately on the intersecting streets 25 and for definite time limits.

Other objects are to accomplish the change of signals automatically in definite cycles, to provide manual control for the signals, and to provide signals which may be set to 30 stop all traffic if desired.

In accordance with these objects means are devised whereby the signals are operated substantially in unison, so that substantially parallel lines of travel are permitted upon 35 one street, and are not permitted upon the transverse lines of travel, the signals being of such a nature that the sign devices have a common display position, and alternately move into the display position to indicate 40 that the traffic is open or closed for respective lines of travel, and means are devised whereby the intervals between change of signals are varied relatively and proportionally.

45 Other objects and advantages may appear from the subjoined detail description.

Upon the annexed drawings, Figure 1 is a sectional elevation of a signal device embodying my invention, and taken on line X¹, 50 of Fig. 2, with the internal structure and operative parts in elevation. Fig. 2 is a sectional elevation on line X², of Fig. 1. Fig. 3 is a sectional and detail view of a semaphore signal on line X³, of Fig. 2. Fig. 4 55 is a diagram showing the signals and the electric connections therefor, and electric

elements included in an apparatus to control intersecting lines of traffic. Fig. 5 is a perspective view of a signal and the housing therefor constructed without the control device as shown in Figs. 1 and 2.

Referring to the drawings, the signal devices employed for the purpose of my invention are preferably adapted to indicate positively the opening of streets to traffic and the closure of streets to traffic by the movement of characteristic signs to display position, indicating one or the other of these two conditions of the streets, and comprise 60 housings 11, with interior operative elements 65 12, hereinafter described, and movable sign semaphores 15 and 16. A set of signal apparatus comprises four of these housings 70 with included operative apparatus and semaphores, designed to be displayed at intersecting streets, and arranged with the semaphores facing the approaching line of traffic thereon. The housings and associated signals and semaphores are identical 75 in construction and operation, with the exception that one is provided with an integral control box 12. The semaphores are both movable into and out of the display position, and are provided with suitable traffic insignia, one having thereon the word 80 "Stop" and the other having inscribed thereon the word "Go". A detail description 85 of the housing provided with a control box and the included operative parts and semaphore signals, will suffice for an understanding 90 of the invention.

The housing 11 is provided with two transverse and rotative horizontal shafts 13 and 14, on which are mounted respectively, the fixed semaphores 15 and 16. A flexible 95 cord 17 connects semaphore 15 with a plunger 18, working in a solenoid 19, which, when energized, will pull the plunger downward and thereby raise the semaphore to the display position. Upon deenergization of 100 the solenoid, the semaphore is forced by gravitation to resume the non-display position.

A drum 20 is mounted on axial shaft 13, and is adapted for a limited and independent rotative movement relative to the shaft, and is adapted to be actuated through an arc of ninety degrees to operative and inoperative positions relative to the semaphore 15. A cord 21, preferably a chain, is connected at one end to the periphery of drum 105 20, and at the opposite end to a plunger 22.

The plunger 22 works within solenoid 23, which is longitudinally disposed in semaphore 15, as shown in dotted lines in Fig. 2, and in section in Fig. 3. Upon energization 5 of solenoid 23, the plunger 22 is forced to move relatively toward the free end of semaphore 15, thereby rotating drum 20 through an arc of ninety degrees to a position relatively operative to the semaphore, the drum 10 20 being thereby forced to move or rotate synchronous with the movement of semaphore 15, fixed to shaft 13. In the operative position of drum 20, which is constantly maintained relative to semaphore 15, upon 15 closure of switch 37, and the energization of the circuit comprising conductor 49, switch 37, branch conductors 38, and solenoids 23, influencing the plunger 22 and the flexible connecting cord 21, the slack is taken up in 20 cord 24 connecting drum 20 with drum 25, fixed to semaphore 16, and therefore, as semaphore 15, weighted to counterbalance the combined weight of semaphore 16 and plunger 18, swings to non-display position, 25 the semaphore 16 will be actuated to display position, and reversely, as semaphore 15 is operated to display position, the semaphore 16 will be actuated by gravitation to the non-display position, the cord 24 winding from 30 one drum to the other when the semaphores are actuated to a change of display position. One semaphore is mounted above the other, and each semaphore is adapted to swing to a horizontal display position, the words 35 "Stop" and "Go," being alternately displayed upon change of position of the semaphores. The movement of the semaphores is simultaneous and effective for the presentation of signals adapted to control intersecting lines of traffic.

Automatic timing devices contained within control-box 12, consist of a shaft 26, on which is mounted the gear-wheel 27, in mesh with a pinion 28, which is driven by motor 45 29. A rheostat 30, in connection with the motor, will regulate the speed thereof, or may be employed as a cut-out switch, if desired. The motor controlling rheostat 30 is 50 preferably of any well known form used to control the speed of electric motors, there being many devices of this character on the market.

Wheel 27 is normally in constant rotation, being driven by motor 29, and is provided with a fixed cam 31 on one side thereof. A radial arm 32, provided with a cam 33, is clamped to the opposite side of the wheel. The cam 33 is adjustable to various positions relative to fixed cam 31. Cams 31 55 and 33 alternately actuate a three-point snap switch 34, which is preferably of the push-button type, and designed to alternately open and close two circuits, there being many types of switch of this character 60 on the market. The switch illustrated is

provided with elongated push-buttons 52, working in the guide 53, and is twice actuated during one revolution of the timing wheel 27, as the buttons 52 lie in the paths of travel of cams 31 and 33. A diagram of 70 switch 34 is shown in Fig. 4, showing that the same may be alternately connected to secondary conductors 35 and 36, thereby controlling signal circuits as hereinafter set forth.

75

It is to be understood that I do not claim as my invention any of the electrical elements employed in constructing this device. The solenoids, wire conductors, switches, motor, and speed-controlling rheostat, are 80 all of standard construction, on the market, and in practical use. My invention resides in the particular combination of these elements to produce an automatic traffic signal apparatus as defined in the appended claims. 85 Therefore, the specific detailed construction of these electric elements is omitted. Equivalent electrical elements and devices may be substituted where desirable.

A switch 37 is preferably a snap switch 90 of any well known form of single-pole switch, which will connect a secondary wire with a primary wire, there being many switches of this character on the market and in practical use. A diagram of this switch 95 is shown in Fig. 4, in which the same is adapted to connect the primary wire 49, with a series of secondary wires 38, which include within their circuits the solenoids 23, in connection with the primary wire 44. 100 It may be seen that by closing switch 37, the circuits including wires 38 and solenoids 23, are bridged between the primary wires 44 and 49, energizing the solenoids, and through corresponding movement of plungers 22 and cords 21, placing drums 20 in relative position for synchronous movement with their respective signal semaphores 15, and thereby tensioning the connecting cords 24, whereby the associated signal semaphores 110 also become operative. Conversely, upon opening switch 37, all signal semaphores will assume the inoperative and non-display position.

The electric conductors may be arranged 115 to pass through conduit 51, and thence to one or another of said housings.

Referring to Fig. 4, it may be seen that solenoids 19, when energized, serve to actuate signals on diagonally opposite street 120 corners, to the display position, as herein described. Similar solenoids 41, when energized, serve to actuate signals on the remaining and diagonally opposite street corners. The primary wires 44 and 49, comprise the supply mains from which various secondary circuits are taken for actuating the various electrical elements associated with the signal devices.

Assuming switch 34 to be in the position 130

- as shown, the closed circuit formed thereby, will include the primary wire conductor 49, switch 34, secondary wire conductor 36, conductors 45 and 46, solenoids 19, conductors 47 and 48, and primary conductor 44, and serves to effect the display of "stop" signals actuated by solenoids 19. In this position, the associated "go" signals, actuated by gravity, will automatically 5 assume and maintain the non-display position. On closing a circuit comprising switch 34, conductors 49, 35, 39, 40, solenoids 41, and conductors 42, 43, and 44, the "stop" signals affected by solenoids 41 will 10 assume the horizontal display position, thereby withholding permission for traffic upon the intersecting lines of travel. All "stop" signals return by gravitation to non-display position, and all "go" signals automatically 15 assume the display position when the circuits controlled by switch 37, and including conductors 38 and solenoids 23, are closed, and the circuits controlled by switch 34 are opened. 20
- 25 The traffic officer may, by manipulation of the combined cut-out switch and speed controlling rheostat 30, cut out the operation of the motor, thereby leaving the signals in position for permission of traffic upon one 30 of the intersecting streets, or he may, by manipulation of switch 50, place both sets of solenoids 19, and 41, in circuit with the primary conductors 44 and 49, thereby actuating all "stop" signals to display position. 35 or he may, by manipulation of the switch 37, cut out the circuit energizing solenoids 23, thereby rendering the semaphores 15 and 16 relatively inoperative, serving to place all signals in the non-dis- 40 play position.
- If, in the judgment of the traffic officer, the traffic should be changed at longer intervals, he will manipulate the speed controlling rheostat so that the motor will operate 45 at a reduced speed, and conversely, increasing the speed of the motor will shorten the intervals between change of signals. Thus the intervals between change of signals is varied proportionally. If traffic be greater 50 on one street than on the other, the traffic officer will adjust the movable cam 33 relative to the fixed cam 31, thereby varying the intervals between the actuation of switch 34, and varying the traffic permission upon the 55 intersecting streets, relatively.
- While the device shown and described, is well adapted for serving the purposes of the invention, it is to be understood that no limitation is made to the precise structural 60 details exhibited in the drawings, but changes may be made without departing from the spirit of the invention or sacrificing any of its advantages, the apparatus including sign devices substantially at each 65 corner of intersecting streets, means for simultaneously operating them, means for varying the intervals in the cycle of operation relatively and proportionally, and arranging the sign devices so that traffic signals of similar import are presented to 70 parallel lines of travel, and signals of the opposite import are presented to the intersecting lines of travel upon intersecting streets. 75
- What is claimed is:
1. In a traffic signal, a housing, axial bearings in said housing, one bearing located above the other, semaphores mounted to swing on said bearings, a plunger, a cord connecting the upper semaphore and plunger, a solenoid to actuate the plunger and throw the upper semaphore to display position, said semaphore falling by gravity to non-display position when the solenoid is deenergized, and connecting means between 80 the upper and lower semaphores whereby the lower semaphore is raised as the upper semaphore falls. 85
  2. In a traffic signal, two semaphores, one of which is located above the other, electro-magnetic means to actuate one of the semaphores to display position, connecting means whereby one of the semaphores is raised as the other is lowered, and means to alternately energize and deenergize the solenoid. 90 95
  3. In a traffic signal, two semaphores, one of which is located above the other, and drops by gravity to the non-display position, electro-magnetic means to actuate the superposed semaphore to display position, connecting means whereby the lower semaphore is raised as the upper semaphore falls to non-display position, means for maintaining an operative tension of the connecting means, and means for releasing the tension main- 100 taining means. 105
  4. In a traffic signal, two semaphores, one of which is located above the other, a tensioned connecting cord whereby the semaphores are simultaneously operative, and 110 means for releasing the tension of the cord to make the signals inoperative. 115
  5. The combination with two semaphores, one of which is located above the other, of a cord connecting means between the semaphores whereby the signals are simultaneously operative, and means for varying the tension of the connecting cord. 120
  6. In a traffic signal, two semaphores, one of which is mounted above the other, a cord connecting means between the semaphores, electro-magnetic means for tensioning the cord to make the semaphores simultaneously operative, and means to deenergize the mag- 125
  7. In a traffic signal, two semaphores, one of which is mounted above the other, electro-magnetic means to actuate the upper semaphore, a cord connecting means between the semaphores, and electro-magnetic means for 130

tensioning the cord to make the semaphores operative, means to alternately energize and deenergize the first-named magnetic means, and independent means to energize and deenergize the last-named magnetic means.

8. In a traffic signal, two semaphores, one of which is superposed above the other, and both of which are oscillative to display and non-display positions, a cord connecting means whereby the semaphores will oscillate simultaneously, electro-magnetic means to operate the upper semaphore, and means to render the cord connecting means inoperative.

10 9. In a traffic signal, two semaphores oscillative upon pivot centers in different planes, a drum carried upon one pivot center, a drum affixed to one of the semaphores, a cord connecting means winding in opposite 20 directions on the two drums, and means for varying the position of the first-named drum relative to its co-operative semaphore.

10. In a traffic signal, two semaphores oscillative upon axial bearings, one of which is mounted above the other, a drum mounted upon the upper bearing, means for varying the position of the drum relative to the upper semaphore, and a cord connecting means between the drum and the lower semaphore, 30 said lower semaphore being operative or inoperative in accordance with the position of the drum.

11. In a traffic signal system, a source of electric energy, two solenoid circuits, signals 35 operated to "stop" position when the solenoid circuits are energized, switch means to throw either solenoid circuit in connection

with the source of electric energy, other signals operated to "go" position, a cord connecting means between the "stop" and "go" signals, electro-magnetic means for tensioning the cord connecting means, and an independent switch to connect the electro-magnetic means with the source of electric energy.

40 12. The combination with a housing, of two axial shafts rotatively and horizontally mounted therein, one being superposed above the other, semaphores fixed to the rotative shafts and movable to horizontal display positions, a solenoid within the housing, a plunger working within the solenoid, a flexible cord connecting the plunger with the uppermost semaphore and operative to force the semaphore to display position 5 when the solenoid is energized, means for energizing the solenoid, a drum independently mounted on the uppermost axial shaft, electro-magnetic means for maintaining the independently mounted drum in synchronous movement with the uppermost semaphore, a drum fixed to the lowermost semaphore, and a flexible cord connected to said drums adapted to wind from one to another upon movement of the semaphores in change 60 65 of signal position.

In testimony whereof I hereunto affix my signature, this 6th day of March, in the year 1918.

FRANK J. HUSBANDS.
